Primary Examiner—Mimosa De(74) *Attorney, Agent, or Firm*—Hoffmann & Baron, LLP(57) **CLAIM**

The ornamental design for a hutch, as shown and described.

DESCRIPTION

FIG. 1 is a perspective view of the hutch according to my claimed design; the two shelves and the bottom horizontal support are not part of the claimed design and are shown in phantom;

FIG. 2 is a top plan view thereof;

FIG. 3 is a front elevation view thereof; and,

FIG. 4 is a right side elevation view thereof, the left side elevation view is a mirror image of the right side elevation view and therefore is not shown.

The bottom and rear of the hutch are not part of the claimed design and therefore are not shown.
